DRIVE SHAFT HOUSING FOR OUTBOARD MOTORS

Elmer C. Kiekhaefer, Cedarburg, Wis.

Application September 5, 1947, Serial No. 772,344

7 Claims. (Cl. 115—17)

1

This invention relates to outboard motors and has as its primary object the provision of a generally improved outboard motor.

In the outboard motor art, it is desirable to use a water system for cooling the engine—a system in which the water is drawn up from the lake or river, then circulated through the water jackets surrounding the engine cylinders and then expelled back into the lake or river. In the outboard motor art, it is also desirable to expel exhaust gases from the engine beneath the water level of the lake or river.

Various types of constructions are in use commercially today for providing water systems and exhaust systems for outboard motors. Many of these constructions require the use of three or more separate castings with separate exhaust systems and separate water systems. My invention contemplates the use of two single piece castings, one of which may be referred to as the drive shaft housing and the other of which may be referred to as the propeller shaft housing. The water system and the exhaust system are incorporated within said housing thereby providing a simplified construction in which machining costs are greatly reduced and the assembling of the outboard motor is facilitated. By utilizing these two single piece castings with the water and exhaust systems incorporated within said casting, I have made it possible to completely streamline the exterior of said castings so that no water resisting obstructions appear on the exterior surface of said castings.

One important object of my invention is to provide an underneath structure, commonly referred to in the art as a "lower end unit," in which I utilize only two single piece castings which are united together to form a unitary underneath structure.

Another object is to lubricate the drive shaft and spline.

Another object of my invention is to provide a drive shaft housing consisting of a single piece casting in which an anti-cavitation plate is cast integrally with said drive shaft housing.

Another object of my invention is to provide a two piece underneath structure in which machining costs are reduced to a minimum.

Another object of my invention is to provide novel means for securing the drive shaft housing and the propeller shaft housing together whereby no obstructions appear on the exterior surface of said housings.

Another object of my invention is to provide an improved water cooling system.

2

Another object of my invention is to provide an improved exhaust system in which relief ports permit expulsion of exhaust gases when back pressure in the primary exhaust passage becomes so great as to impair efficient operation of the engine.

Another object is to provide a novel co-pilot device for steering in a set course.

Other objects and advantages will become apparent upon reading the following specification and upon examination of the drawings in which:

Fig. 1 is a side elevational sectional view of my outboard motor;

Fig. 2 is a detail side elevational view of the drive shaft housing;

Fig. 3 is a detail front elevational view of the drive shaft housing;

Fig. 4 is a top plan view of the drive shaft housing;

Fig. 5 is an underneath plan view of the drive shaft housing;

Fig. 6 is a view of the drive shaft housing taken on line 6—6 of Fig. 2;

Fig. 7 is a fragmentary view of the co-pilot device enlarged from Fig. 1;

Fig. 8 is a detail view of the inner end of the tiller;

Fig. 9 is a detail view of the friction plate to which the inner end of the tiller is secured;

Fig. 10 is a detail top plan view of the swivel bracket which supports the drive shaft housing and which accommodates the co-pilot device;

Fig. 11 is a fragmentary detail front view of the swivel bracket;

Fig. 12 is a detail plan view of the spring plate which is a part of the co-pilot device; and

Fig. 13 is a detail view of the clamp plate which is a part of the co-pilot device.

It will be noted that in Figs. 10 and 13 I have shown the friction buttons secured to the swivel bracket and clamp plate respectively. It will also be noted that the sectional views of Figs. 1 and 7 are taken generally on the irregular center line as indicated in Fig. 10.

In the preferred embodiment of my invention I have shown an outboard motor in which the power unit 2 may be housed in an outer casting 3. The drive shaft housing 5 is secured directly to the engine block 6 and to crankcase 7 by means of bolts 8, one of which is shown in Fig. 1. By referring to Fig. 4, it will be noted that I have provided the upper end of drive shaft housing 5 with an adequate number of bolt holes 9 for bolts 8. By referring to Fig. 4, it will be noted that the upper facial extremity of drive

shaft housing 5 defines a cross sectional area which has substantial width as well as substantial length whereby a large area is provided for supporting the power unit above the drive shaft housing. This is important since the power unit receives its entire support from the drive shaft housing 5.

The drive shaft housing 5 is provided with an opening 11 at its upper extremity and an opening 12 at its lower extremity and a third opening 13 in mouth piece 14. A continuous passage 15 connects each of said openings. It will be noted that the passage 15 is largest in cross sectional area at the opening 11 and is smallest in cross sectional area at the openings 12 and 13. Said passage 15 is continuously convergent from opening 11 to opening 12. It will be noted that passage 15 flares rather sharply outwardly beginning at point 17 thereby providing a large cubical area in the upper region of said drive shaft housing 5. This enlarged cubical area provides an expansion chamber for the exhaust gases immediately after they are discharged from the exhaust ports (not shown) in the cylinders. Said gases then travel through the gradually restricted passage 15 until they are eventually expelled at opening 13.

It will be noted that drive shaft housing 5 consists of a single piece casting having an upper flared region 19, an intermediate convergent region 20, and a lower shoe portion 21 which extends outwardly and rearwardly and is inclined slightly downwardly with respect to the intermediate region 20 of housing 5. The housing 5 is provided with a splash guard 22 and an anti-cavitation plate 23, both of which are cast integrally with said housing. The splash guard serves to deflect the upwardly traveling waves created by the anti-cavitation plate cutting through the water. The anti-cavitation plate 23 in addition to serving the normal function of deflecting water into the propeller blades and preventing voids at the propeller also serves as an underneath closure for shoe 21. The mouth piece 14 is a downward continuation of the shoe portion 21 and extends beneath the lower face of anti-cavitation plate 23 so as to overhang the propeller 24. The mouth piece 14 and its opening 13 are directed angularly downwardly and rearwardly with respect to propeller 24 whereby the slip stream of propeller 24 causes an outward suction at orifice 13 thereby causing an aspirating effect on the exhaust gases being expelled at orifice 13.

Drive shaft housing 5 is provided at its front longitudinal edge 26 with a pair of aligned bosses 27 and 28 which are provided with axially aligned internal bores 29 and 30. Said housing 5 has recessed regions 31 and 32 thereby providing flat bearing faces 33 and 34 with opposed internal bores 35 and 36, the reason for which will be hereinafter described.

Housing 5 is also provided at its upper end with an internal boss 40 which receives the upper end of tie rod 41. It will be noted that boss 40 provides the necessary wall thickness to accommodate the opposed bores 35 and 36 thereby serving a double function. Housing 5 is also provided with an internal boss 36 which receives one end of the water inlet pipe 37. An opening 38 in engine block 16 establishes communication between the inlet water pipe 37 and the water jacket 39 of said engine block 6. Housing 5 is also provided with an internal boss 42 which screw-threadedly receives connecting bolt 43.

Drive shaft 44 extends through the interior of housing 5 into propeller housing 45. It will be noted that the water pipe 37, drive shaft 44, tie-rod 41 and connecting bolt 43 are all located interiorly of housings 5 and 45 so as to eliminate all obstructions which would tend to interrupt the streamlined exterior surface of housings 5 and 45.

It will be noted that the underneath structure consists of only two castings, the drive shaft housing 5 and the propeller shaft housing 45 which are connected together by means of tie-rod 41 and connecting bolt 43. Thus there are only two castings to be aligned for the assembly of drive shaft 44, tie-rod 41, bolt 43 and water pipe 37. Consequently, the number of machined openings to be aligned are kept at a minimum and machining tolerances need not be held as closely as in the constructions of the prior art. Machining costs are therefore materially reduced and spoilage of parts during the machining operations is reduced to a minimum.

The outboard motor assembly is secured to the transom 56 of a boat between clamp screw 59 and the opposing wall of bracket 59. A bracket 60 is carried by bracket 59 by means of a horizontal pivot pin 54 so as to be swingable up and down relative thereto. Bracket 60 is provided with an elongated cylindrical sleeve portion 61 having an internal bore for receiving pivot pin 62. A pair of bushings 63 and 64 are mounted in bosses 27 and 28 and serve as bearings for pivot pin 62. Said bushings consist of internal and external mating metal sleeves with a rubber sleeve interposed between and bonded to said metal sleeves. Said bushings prevent transmission of vibration to brackets 59 and 60 as well as serving as bearings for pin 62. Sleeve portion 61 has an enlarged portion 61a with a bore 66 for receiving sleeve 67. A friction plate 68 is secured to sleeve 67 so as to be rigid therewith. Said sleeve 67 is rotatable in bore 66 of sleeve 61. A tiller 83 embraces boss 28 and is rigidly secured to friction plate 68 by means of bolts 84 extending through bolt holes 84a and being threaded into holes 84b. It will be noted that the friction plate 68 is supported by means of sleeve 67 within bore 66. Said friction plate 68 has a U-shaped walled region 100 which embraces housing 5 in the recessed regions 31 and 32 and is connected to housing 5 only through the medium of a pair of compression springs 101 and 102 which are received in the holes 35 and 36 in housing 5 and which are biased against opposite walls of the U-shaped walled region 100, as viewed in Fig. 9. The springs 101 and 102 thus serve to establish connection for steering purposes between drive shaft housing 5 and tiller 83 (which is rigid with friction plate 68) and also serve to prevent transmission of vibrations from housing 5 to tiller 83.

The pin 62 is preferably rotatable within bushings 63 and 64 as well as with respect to sleeve 61 and rotation of drive shaft housing 5 relative to bracket 60 is permitted by means of bearing bushings 63 and 64 and sleeve 61. I prefer, however, to provide a fairly snug fit between bearings 63 and 64 and pivot pin 62 so that rotation of housing 5 relative to bracket 60 is slightly resisted. This snug fitting helps to prevent transmission of vibration from the motor to the boat and also assists in the operation of my co-pilot device which will hereinafter be described. It will be noted that the internal metal sleeves of bushings 63 and 64 are crimped (as at 110 in

Fig. 7) to restrain pin 62 from up and down movement within sleeve 61.

Viewing Fig. 10, it will be noted that bracket 60 is provided with an arcuate recessed region 70 providing a path of travel for friction plate 68. A pressure plate 71 is rigidly secured to bracket 60 by means of bolts 72 threaded into bosses 73 and extends through an opening 74 in bracket 60 so as to overhang the recessed region 70 and the friction plate 68. The base 75 in the recessed region 70 is provided with a pair of friction contact buttons 77 and 78 which may be of fiber or some similar material. The free end of pressure plate 71 is provided with another pair of friction buttons 79 and 80 which are preferably in axial alignment with buttons 77 and 78 wherein said buttons frictionally engage the opposite faces of friction plate 68, thereby impeding rotative movement of friction plate 68 and housing 5 relative to bracket 60.

In order to adjust the frictional resistance which is set up between friction buttons 77 and 78, and 79 and 80 and friction plate 68, I have provided a spring plate 86 which is rigidly secured to pressure plate 71 by means of rivet 87. Said spring plate in its intermediate region preferably rests adjacent the underneath surface 88 of boss 89. Adjacent screw 90 which is threaded into boss 89 engages the upper surface of the spring plate 86. When bolt 90 is tightened against spring plate 86, the outer end of said spring plate urges friction buttons 79 and 80 toward buttons 77 and 78 thereby increasing the frictional resistance of said buttons against friction plate 68. In the ideal operating condition of my co-pilot device the frictional resistance between the friction buttons and the friction plate 68 is such as to permit fairly easy rotation of drive shaft housing 5 and the power unit relative to bracket 60 so that there is no laborious effort involved in moving the tiller 83 for free steering of the boat. However, such frictional resistance between the friction buttons and friction plate 68 is sufficient to maintain the drive shaft housing and power unit in a fixed steering position relative to the boat so that a pre-determined steering course for the boat is maintained when the operator releases his grip on the tiller. It will be noted that the spring plate 86 permits fine adjustment of frictional resistance.

To facilitate easy steering of the boat with my outboard motor, I provide a construction in which the steering action may be said to be fully "feathered." It is conventional in the outboard motor art to use the submerged propeller housing and the submerged portion of the drive shaft housing in the manner of a rudder—the entire power unit and "lower end unit" being swung about pivot pin 62 to steer the boat. The knife-like front longitudinal edge 26 of drive shaft housing 5 cuts the water in the manner of a rudder. Viewing Fig. 1 it will be noted that pivot pin 62 is substantially parallel to and is located forwardly of the water impinging longitudinal front edge 26 of drive shaft housing 5. Thus the water cutting front edge 26 trails the steering pivot 62 giving a "feathered" steering action. If the front edge 26 of housing 5 were located ahead of pivot pin 62 so as to impinge the water ahead of the steering pivot, then a somewhat wagging condition of the drive shaft housing and power unit relative to the boat would result, making it laborious to steer the boat.

Referring to Fig. 1, it will be noted that the water system for my outboard motor includes water inlet ports 105 located in front of the propeller in the underneath wall of propeller housing 45. A pump 106 forces the water up through passage 107 into water pipe 31, thence through opening 38 into water jackets 39.

Engine block 6 is provided with an exhaust passage (not shown) which extends into communication with the expansion chamber 50 at the upper end of housing 5. The engine block 6 is also provided with a water outlet passage (not shown) which establishes communication between water jacket 39 and expansion chamber 50. Said water passage also has a by-pass which communicates with chamber 51 in casting 52. A plate 57 is interposed between the outer extremity of housing 5 and casting 52 and serves to close off chamber 50. Said plate 57 is provided with an opening 55 which serves as a water outlet opening. The water travels through outlet opening 55 down through bore 97 in pivot pin 62 and is ultimately expelled at the lower outlet 98 of pin 62. The primary water outlet, however, is through passage 15 in drive shaft housing 5; said water helping to cool the exhaust gases which are also expelled through passage 15.

Referring to Fig. 1, it will be noted that in addition to the primary underwater exhaust outlet 13, I have provided supplementary exhaust outlets for expelling the exhaust gases above water when back pressure in passage 15 becomes too great. When the motor is idling, the water enters passage 15 through orifice 13 and creates pressure which is greater than the pressure of the exhaust gases coming from the cylinder exhaust ports thereby preventing escape of the exhaust gases through outlet 13. I have therefore provided bleeder size exhaust port holes 94 in the upper rear wall of housing 5, the said ports being always above water level. Thus when the back pressure in passage 15 becomes too great, the exhaust gases are by-passed through ports 94. I have also provided a slot 95 in the upper end of housing 5 which slot communicates with chamber 96 between plate 57 and pin 62. It is thus seen that the exhaust gases can escape through slot 95 and thence through the internal bore 97 of pin 62 and are expelled at the outlet 98.

Referring to Fig. 1, it will be noted that the drive shaft 44 extends through the interior of drive shaft housing 5, consequently it is continuously subjected to a spray of water which is being discharged through the interior of the drive shaft housing while the motor is operating.

In order to reduce rusting and corroding of the drive shaft, I have provided a means for running a continuous trickle of lubricant down the entire length of the drive shaft to keep said shaft in a "greasy" or lubricated condition. The crank case 7 which is secured to the engine block 6 is provided at its open end with a flange portion 109 to which the cover plate casting 52 is secured. By drilling a small hole 110 in the casting 52, I establish communication between the interior of crank case 7 and the crank shaft 114. The casting 52 has a downwardly depending hub portion 112 with an inwardly directed internal annular shoulder 113 (shown best in Fig. 7). The lubricant, which is always present in the interior of crank case 7 (said lubricant being mixed with the gasoline that enters through the crank case before being transferred to the explosion chamber of the cylinder), is forced

through the passage 110 on the downward compression stroke of the piston 114 and travels along the rotating crank shaft 111 and is eventually expelled at the opening 115 in the hub 112 where it continues to trickle along the rotating drive shaft 44. It can be seen that the rotation of drive shaft 44 causes the otherwise inert lubricant to become spread about over the external surface of drive shaft 44 while gravity causes it to trickle downwardly along said shaft, thereby substantially lubricating the entire shaft.

It is significant to note that the annular shoulder 115 serves to deflect some of the lubricant toward the spline teeth 116 on drive shaft 44 and the spline grooves 117 in the crank shaft 111 and with the presence of capillary action the lubricant works up along the spline grooves and teeth to provide adequate lubrication for same.

It is important to note that the passage 110 is largely closed off by the flange 109 of crank case 7 thereby permitting only a small trickle of lubricant to pass through the passage 110 and the size of the passage 110 is small enough so as not to interfere with obtaining the required amount of compression in the crank case for efficient operation of the engine.

Having thus described my invention what I claim is:

1. An outboard motor comprised of a power unit, a drive shaft housing disposed beneath said power unit, a boat engaging member, pivotal means vertically disposed forwardly of said drive shaft housing connecting said drive shaft housing to said boat engaging member, an internal passage in said pivotal means from the upper end thereof opening downwardly, said power unit including a water cooling system discharging into the upper open end of said pivotal means whereby said passage having communication with the water cooling system of the power unit provides for discharge of the water forwardly of said drive shaft housing.

2. An outboard motor comprised of a power unit, a drive shaft housing disposed beneath said power unit, a boat engaging bracket, a pivot pin supported by the boat engaging bracket and pivotally supporting the drive shaft housing relative to the boat engaging bracket, a passage extending through said pivot pin, said passage having communication with the water cooling system of the power unit and said passage having restricted communication with the exhaust system of said power unit.

3. In an outboard motor comprised of a power unit, a drive shaft, and a propeller driven thereby; an exhaust system for said outboard motor including a drive shaft housing having a downwardly converging internal passage extending therethrough and opening into the lower end of said housing, said passage having communication with an exhaust opening of the power unit, the opening in the lower end of the housing being the primary outlet for exhaust gases from the power unit, secondary outlets for exhaust gases, said secondary outlets including bleeder size holes in the upper rear wall of the drive shaft housing and in the upper forward wall of the drive shaft housing.

4. An outboard motor comprised of a power unit, a drive shaft and a propeller driven thereby, a drive shaft housing disposed beneath the power unit, a boat engaging member, means for supporting the drive shaft housing and power

unit relative to the boat engaging member, said drive shaft housing having an internal passage opening into the upper and lower ends of said housing, said lower opening being normally submerged in water during operation of the outboard motor, said internal passage having communication with an exhaust opening of the power unit, the lower opening in said drive shaft housing being the primary outlet for exhaust gases from the power unit, an internal passage in the aforementioned supporting means, a secondary exhaust outlet comprised of an opening in the upper non-submerged forward wall of the drive shaft housing, said last opening having communication with the internal passage in the supporting means.

5. An outboard motor comprised of a power unit, a drive shaft and a propeller driven thereby, a drive shaft housing disposed beneath the power unit, a boat engaging member, a pivot pin disposed adjacent to but exteriorly of the drive shaft housing and being adapted for pivotally supporting the power unit and drive shaft housing relative to the boat engaging member, and exhaust passage within the drive shaft housing and having an outlet at the lower end normally submerged under water, an internal passage in the pivot pin, a secondary exhaust outlet in the non-submerged portion of the drive shaft housing, said secondary exhaust outlet having communication with the internal passage in the pivot pin.

6. An outboard motor comprised of a power unit, a drive shaft and a propeller driven thereby, a drive shaft housing disposed beneath the power unit and having its upper end open toward the power unit, a crankcase, a plate interposed between the crankcase and drive shaft housing to close off the housing relative to the power unit, a chamber on the crankcase side of said plate having communication with the water system of the power unit, an enclosed passage adjacent to but exteriorly of the drive shaft housing, an opening in said plate, said opening being in registry with the enclosed passage for expulsion of water from the power unit.

7. An outboard motor as set forth in claim 6 wherein there is an exhaust opening adjacent the plate and extending through the wall of the drive shaft housing into communication with the enclosed passage.
